EX

W0-12,402

AMULET -OR- CHARM

UNITED STATES PATENT OFFICE.

LE ROY W. FAIRCHILD, OF NEW YORK, N. Y.

DESIGN FOR AN AMULET.

SPECIFICATION forming part of Design No. 12,402, dated August 9, 1881.

Application filed April 5, 1881. Term of patent 7 years.

To all whom it may concern:

Be it known that I, LE ROY W. FAIRCHILD, a citizen of the United States, residing at the city of New York, in the county and State of New York, have invented a new and original 5 Design for an Amulet or Charm, of which the following is a specification, reference being had to the accompanying photograph, forming part thereof.

10 The accompanying photograph represents my design in elevation, and will serve to illustrate the same.

The design consists of a body, I, made in the form of a canteen, with a compass, B, inserted in one side, and having a neck or extension constructed to form a whistle, C, as 15 shown in the accompanying photograph. A bail, D, is pivoted to the body I at each side, as shown at E and E', and has a ring, F, at

its upper end, as shown, and which will permit the device to be used as a pencil-case or as a case for any similar small implement.

The design may be made up in metals of different kinds or of the same metal of different shades, and it may be further ornamented 25 by engraving, stamping, or enameling figures of any desired style upon its surface, as may be desired.

Having thus described my invention, what I claim is—

The herein-described design, consisting of 30 the canteen I, with the compass B, whistle C, and bail D, substantially as shown.

LE ROY W. FAIRCHILD.
